LUMBER SORTING APPARATUS

Curt F. Setzer and Herbert W. Ryan, Sacramento, Calif., assignors to Setzer Forest Products, Inc., Sacramento, Calif., a corporation

Application February 24, 1948, Serial No. 10,348

3 Claims. (Cl. 214—11)

1

This invention is directed to, and it is an object to provide, novel apparatus for sorting green lumber as cut in a sawmill; the apparatus being especially useful to sort lumber according to size (width or thickness), or for grade.

Another object of the invention is to provide a lumber sorting apparatus which includes a plurality of separate racks, and manually controlled gates corresponding to the racks arranged to function, selectively, to deflect individual pieces of lumber, of the same size or grade, from a feed conveyor into the corresponding rack.

An additional object of the invention is to provide a lumber sorting apparatus, as above, wherein the racks are elongated and comprise gravity feed conveyors; there being releasable stop units associated with these conveyor racks to the end that a load or "package" of sorted lumber may be accumulated in each rack and then released for further handling.

A further object of the present invention is to provide a lumber sorting apparatus, as in the preceding paragraph, in which the stops are manually releasable, and of novel construction and operation.

A further object of the invention is to produce a practical and reliable lumber sorting apparatus and one which will be exceedingly effective for the purpose for which it is designed.

These objects are accomplished by means of such structure and relative arrangement of parts as will fully appear by a perusal of the following specification and claims.

In the drawings:

Figure 1 is a somewhat diagrammatic longitudinal elevation of the novel lumber sorting apparatus.

Figure 2 is an enlarged fragmentary plan view illustrating one of the gates between the feed conveyor and the rack assembly.

Figure 3 is a diagrammatic view of the fluid pressure control system as is employed for each of the gate actuating power cylinders.

Figure 4 is an enlarged fragmentary elevation showing one of the releasable stop units in operative position.

Figure 5 is a similar view, but shows such stop unit released.

Figure 6 is a cross section on line 6—6 of Fig. 4.

Referring now more particularly to the characters of reference on the drawings, the novel lumber sorting apparatus comprises an upstanding frame, indicated generally at 1, which is mounted atop thereof with a powered endless feed conveyor 2 which includes a transversely

2

spaced pair of longitudinal feed chains 3; the conveyor 2 extending to a discharge point at the upper end of a forwardly and downwardly inclined lumber chute 4 which includes a plurality of transversely spaced, but parallel, chute beams 5.

Beyond the chute 4 there is an elongated rack assembly 6 which includes a plurality of longitudinally extending vertically spaced racks 7, each of which is in the form of a gravity feed conveyor sloping downwardly in a direction away from the chute 4.

Each of the gravity feed conveyor racks comprises a pair of transversely spaced longitudinal beams 8, each fitted with a multiplicity of transverse axis rollers 9 which project above said beams; the latter being carried on cross beams 10, which in turn are supported by posts 11.

At their discharge ends the gravity feed conveyor racks discharge onto a powered, endless carry-off conveyor unit 12; said unit being actuated by a motor 13 through the medium of a drive 14.

Except for the lowermost conveyor rack 7, said racks terminate at their forward ends adjacent, but short of the chute 4; the spacing between these parts being sufficient to permit lumber to slide down said chute 4 without structural interference. The racks 7, by predetermination, correspond to lumber of given size (width or thickness) or a given grade.

The present invention contemplates the employment of a mechanism hereinafter described to sort lumber from the conveyor 2, and to cause its delivery, onto the corresponding rack 7; such mechanism comprising:

In cooperative relation to the forward end of each rack 7, except for the lowermost one which runs directly to the chute 4, there is a normally open deflector gate 15 associated with the chute 4 and adapted, when closed (swung upwardly and rearwardly), to deflect lumber from said chute onto the corresponding rack 7.

Each such deflector gate 15 includes a cross shaft 16 journaled in connection with the chute beams 5, and having deflector arms 17 projecting radially therefrom, normally in a downward direction substantially parallel to said chute beams 5. In this normal position of the deflector arms 17 the corresponding deflector gate 15 is ineffective or open.

A fluid pressure actuated power cylinder 18 of double acting type is disposed below one of the deflector arms 17 of each deflector gate 15. Each cylinder 18 includes an upwardly projecting

plunger 19 pivoted to the adjacent deflector arm 17, as at 20, while the opposite end of each cylinder is pivoted, as at 21, to a supporting beam 22 below the chute 4 parallel thereto.

The plungers 19 are each normally retracted and are adapted to be controlled to extend and retract the same by a fluid pressure system including a pair of conduits 23 which lead to a four-way control valve 24 which derives pressure from a supply conduit 25 and vents through a conduit 26.

Each four-way control valve 24 is operated by a spring-lifted foot pedal 27 which projects upwardly through an operator's platform 28 supported by the frame 1 below and to one side of the feed conveyor 2 whereby the operator may visually inspect the size or grade of lumber 29 traveling, transversely, on the feed conveyor 2 in spaced relation. Depression of each foot pedal 27 operates the corresponding four-way control valve 24 to cause the related plunger 19 to extend, closing the corresponding deflector gate 15 with the adjacent rack 7.

It will, therefore, be recognized that as each piece of lumber 29 delivers from the feed conveyor 2 to the chute 4 the operator, by foot manipulation of the corresponding pedal 27, can cause closing of the deflector gate 15 corresponding to the conveyor rack 7 into which such piece of lumber should pass in sorted relation. If a piece of lumber, corresponding to the lowermost conveyor rack 7, enters the chute 4 the operator closes no gate and permits such piece of lumber to slide directly from said chute to said lowermost conveyor rack.

With the above described mechanism, accurate and expeditious sorting of lumber from a sawmill can be accomplished; the sorted lumber traveling by gravity down the corresponding conveyor racks 7 but normally being held from escape therefrom by a plurality of corresponding and releasable stop units, each of which is indicated at 30.

The sorted lumber accumulates on corresponding conveyor racks 7 as long as the corresponding stop unit 30 is in operative position. After a load or "package" of lumber accumulates on any given one of the conveyor racks 7, the corresponding stop unit 30 is released whereupon such lumber continues by gravity on its conveyor rack 7 to discharge onto the powered, endless carry-off conveyor unit 12. From the conveyor unit 12, which is then carrying lumber of a sorted, predetermined size or grade, such lumber may be handled in any suitable manner.

The stop unit 30 for each rack 7 is of novel construction and operation, as follows:

A cross shaft 31, journaled in attachment ears 32 affixed to the adjacent posts 11, extends below the longitudinal beams 8 of the related rack and said cross shaft 31 carries a pair of radial stops 33 which normally upstand into the path of lumber on said rack. At one end thereof each cross shaft 31 is fitted with a fixed radial arm 34 having a bearing 35 on its outer end; the axis of such bearing being parallel to a line tangential to the cross shaft 31. A turnable rod 36 is carried intermediate its ends in the bearing 35; axial shifting of said rod 36 being prevented by collars 37 on opposite sides of the bearing. The radial arm 34 is normally disposed at a forward and downward incline whereby the rod 36 normally extends at a forward and upward incline; the upper end of said rod having a lateral handle 38 thereon.

while the lower end of the rod has a lateral foot 39 projecting in the same direction.

In the normal position of each stop unit, with the radial stops 33 projecting into the lumber path, the rod 36 is turned with the lateral foot 39 projecting inwardly so that it then abuts against the forward edge of the adjacent post 11. To release each stop unit the rod 36 is turned a quarter turn by the handle 38, whereupon the lateral foot 39 escapes the adjacent post 11 permitting the radial arm 34 to swing downwardly with the result that the radial stops 33 swing forwardly and lower to a position clear of the lumber path.

The described lumber sorting apparatus, while being relatively simple in its structure, nevertheless provides a practical and reliable structure capable of accomplishing relatively high speed, manually controlled but mechanical sorting of lumber as delivered from a sawmill.

From the foregoing description it will be readily seen that there has been produced a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent is desired:

1. Lumber sorting apparatus comprising a lumber feed conveyor, a chute to which the feed conveyor delivers lumber, the lumber sliding down the chute, a plurality of lumber racks disposed in vertically spaced relation adjacent but beyond the chute, a plurality of normally open lumber deflector gates mounted in connection with the chute and each adapted to close, in lumber deflecting relation, with a corresponding rack, an operator's station adjacent the feed conveyor and chute, and operator controlled mechanism operative to cause selective closing of said gates; the gates each comprising a transverse shaft journaled in connection with the chute, spaced deflector arms radiating in the same normally downward direction from the shaft and clear of the path of lumber on the chute, said operator controlled mechanism causing rotation of the shaft in a direction to swing said arms toward the corresponding rack and into intersecting relation to said path.

2. Lumber sorting apparatus comprising a lumber feed conveyor, a chute to which the feed conveyor delivers lumber, the lumber sliding down the chute, a plurality of lumber racks disposed in vertically spaced relation adjacent but beyond the chute, a plurality of normally open lumber deflector gates mounted in connection with the chute and each adapted to close, in lumber deflecting relation, with a corresponding rack, an operator's station adjacent the feed conveyor and chute, and operator controlled mechanism operative to cause selective closing of said gates; said mechanism including a fluid pressure actuated power cylinder connected to each gate, a fluid pressure control system for each cylinder, a control valve for each system, and a foot pedal to actuate each valve, the foot pedals being readily accessible from said station.

3. Lumber sorting apparatus comprising a conveyor assembly adapted to move lumber in a

predetermined path, a plurality of elongated gravity feed conveyor racks mounted in spaced apart relation adjacent the conveyor assembly, said racks corresponding to predetermined lumber sizes or grades, manually controlled deflector mechanism operative to deflect lumber of such sizes or grades from said path onto corresponding racks, and a normally operative but releasable lumber stop unit cooperating with each conveyor rack remote from its receiving end; said stop units each comprising a cross shaft below the path of lumber on the corresponding conveyor rack, a normally upstanding stop element on the shaft projecting into said last named path, and means releasably securing the shaft against rotation in a stop element lowering direction; said last named means comprising a radial arm fixed on the shaft, a bearing on the arm with the bearing axis in intersecting relation, a rod turnably but axially non-shiftably journaled intermediate its ends in the bearing, a lateral handle on one end of the rod, and a lateral foot on the other end of the rod; there being an abutment which

the foot engages in one rotative position of the rod and clears in another rotative position thereof.

CURT F. SETZER.
